UNITED STATES PATENT OFFICE.

CHARLES H. DUISDIEKER, OF PEKIN, ILLINOIS.

RETORT.

No. 851,409.

Specification of Letters Patent.

Patented April 23, 1907.

Application filed September 25, 1905. Serial No. 279,916.

To all whom it may concern:

Be it known that I, CHARLES H. DUISDIEKER, a citizen of the United States, residing at Pekin, in the county of Tazewell and State of Illinois, have invented certain new and useful Improvements in Retorts; and I do hereby declare that the following is a full, clear, and exact description of the invention, which will enable others skilled in the art to which it appertains to make and use the same.

My invention relates more particularly to retorts such as are used in bone kilns, ore furnaces, etc.

The object of my invention is to provide a retort so constructed as to be better adapted to withstand the heat to which it is exposed; and further to provide means for combining or interlocking the retorts, both of which said objects are designed to prevent deformity of the retorts, on account of the intense heat to which they are subjected.

In bone kilns, with reference to which my invention is specified, but to which it is not confined, longitudinal, tubular retorts are arranged vertically in parallel series, and are provided with suitable inlets at the top of the kiln and outlets at the bottom thereof whereby the bone black is fed into the retorts and discharged therefrom when purified. Flame is blown from the side walls of the kiln transversely through the series of retorts therein so as to strike them about midway of their length, and the flame, as it strikes the retorts, is deflected both upward and downward a considerable distance enveloping a large central portion of each retort. The flame enveloped central portions of the retorts as can readily be seen, become very highly heated, and in the absence of any suitable preventative means bulge and warp under the intense heat, and soon become unsuited for use. In my invention, however, provision is made to prevent this deforming of the retorts, that has heretofore been experienced by increasing the thickness of the wall of the retort where subjected to the greatest heat, and by interlocking the retorts so that the walls thereof are held from bulging and collapsing.

In the accompanying drawings, Figure 1 shows two cylindroidal retorts, provided with my improvements, looking toward the broad sides thereof, the retort at the right of the line $x-x$ being in vertical section. Fig. 2 shows two retorts similar to those in Fig. 1,

looking toward the narrow lateral faces thereof, the retort at the left of the line $z-z$ being in vertical section. Fig. 3 is a plan view of four of my improved retorts showing the method of combining or interlocking. Fig. 4 is an upper end view of one of my retorts showing the varying thickness of the wall. Fig. 5 is an outer end view of one of the pairs of lugs which I employ in combining or interlocking the retorts. Fig. 6 is an end view of the key or wedge which I employ in combining or interlocking the retorts. Fig. 7 shows a top view of the key or wedge which I employ in interlocking the narrow lateral faces of the retorts, and Fig. 8 is a similar view of the key or wedge which I employ for interlocking the broad lateral faces of the retorts.

Similar figures of reference refer to similar parts throughout the several views.

The retorts 1, which are long tubular members, usually elliptical in transverse section as shown in the drawings, have their lower ends inserted in the upper part of the boots 2, which said boots are fitted in openings 3 in the bottom 4 of the kiln, and are usually provided with triplicate openings 5 through which the bone black is discharged from the retorts as it is purified, and the said retorts extend vertically through the kiln to within a short distance of the top 6 thereof. In the said top 6 of the kiln, are openings 7 corresponding with the upper ends of the retorts, through which said openings are inserted 8 slightly hopper shaped members 8 which in turn have their lower ends inserted in the upper ends of the retorts 1, all of which is well known in the art and needs no further mention.

As has been hereinbefore stated, the central portions of the retorts, being enveloped in the flame of the kiln or furnacé, are subjected to intense heat, which decreases at the lower and upper ends thereof. For the purpose of better withstanding the intense heat, the wall of the central portion of the retort which is enveloped in the flame and which is usually about one half the total length is made thicker than the remainder of the retort, as is shown at 9, and is tapered gradually to the thinner portions at the ends. The wall of the upper end or top of the retort is made considerably thinner than the central portion 9, as shown at 10, so that the bone black as it enters the retort will be rapidly heated, and so as to reduce the

weight of the retort. The wall of the lower end or bottom of the retort, while thinner than the central portion 9, is thicker than the upper end 10, as is shown at 11, to give it sufficient strength to support the weight of the retort and the contents. This varying of the thickness of the wall of the retort, not only better adapts the retort to stand the heat of the kiln or furnace, but also makes the burning of the material therein more uniform throughout the length of the retort. As is shown in the drawings, I prefer to make the outer surface of the retort, uniform throughout its length, and have the increased thickness of the wall decrease the transverse area of the internal opening. At intervals throughout the length of the retort, preferably near the upper and lower extremities of the increased thicker portion thereof, as is shown in the drawings, are provided the pairs of lugs 13 on the broad lateral walls and the pairs of lugs 12 on the narrow lateral walls, the said pairs of lugs being, usually integral with the retort. These lugs, as is seen in the drawings have their inner opposite faces 14 converging from the top downward and diverging from their outer ends inwardly toward the retort, and are so placed on the retorts that when the retorts are properly placed in the kiln in parallel series, each pair of lugs 12 and 13 will be opposite a pair of lugs similarly placed on the adjacent retort, so that the key or wedge 15 or 16 will have its ends seated in pairs of lugs on adjacent retorts as is clearly shown in the drawings. The keys or wedges 15 and 16 which I use for combining or interlocking the retorts have their lateral faces, at each end, corresponding to the faces 14 of the lugs within which they are seated, that is the lateral faces converge from the top downward and from both ends inwardly as is evident from the dotted lines in Figs. 5, 6, 7 and 8. The degree of taper of the keys or wedges 15 and 16 is such that the expansion and contraction of the retorts only serves to more firmly unite the retorts, and any tendency toward looseness is obviated because the weight of the key

or wedge holds it firmly against the faces 50 14 of the lugs 12 and 13.

It is desired to have the broad lateral walls of the retorts distanced somewhat farther apart than the narrow lateral walls consequently the keys or wedges 15 which 55 unite the broad lateral walls are somewhat longer than the keys or wedges 16 which unite the narrow lateral faces thereof.

From the foregoing, it will readily be seen that the increased thickness of the central 60 portion of the retort adapts it to better withstand the heat to which it is subjected, and further that the interlocking of the retorts combines them into a rigid structure and holds the walls from bulging, collapsing, 65 warping or any other deformity to which the heat to which they are subjected would have a tendency to cause.

While I have described my invention particularly with reference to bone kiln retorts, 70 I am aware and contemplate its use in any similar kiln or furnace where the retorts are inclined to deform under the intense heat to which they are subjected.

What I claim is:

1. The combination with a plurality of retorts suitably spaced to provide circulating space therebetween, of key seats on the walls of the retorts intermediate of the ends and keys supported by and adapted to engage 80 the key seats on the facing walls of adjacent retorts for interlocking said walls.

2. In a kiln, the combination with a plurality of retorts, key seats on the outer walls of the retorts comprising pairs of lugs having 85 their inner opposite faces converging downwardly and outwardly from the retorts, keys having their lateral faces converging from the top downward and from the ends inwardly, the said keys having their ends 90 seated within key seats on adjacent retorts for uniting the walls thereof.

In testimony whereof I have affixed my signature, in presence of two witnesses.

CHARLES H. DUISDIEKER.
